COMBINATION LIPSTICK HOLDER AND CIGARETTE LIGHTER

Albert Monturo, Brooklyn, N. Y.

Application March 24, 1950, Serial No. 8,754

Term of patent 3½ years

(Cl. D48—27)

To all whom it may concern:

Be it known that I, Albert Monturo, a citizen of the United States of America, residing at Brooklyn, in the county of Kings and State of New York, have invented a new, original, and ornamental Design for a Combination Lipstick Holder and Cigarette Lighter, of which the following is a specification, reference being had to the accompanying drawing, forming a part thereof, wherein:

Fig. 1 is a top plan view of a combination lipstick holder and cigarette lighter, showing my new design;

Fig. 2 is a side elevational view thereof in closed position; and

Fig. 3 is a side elevational view thereof in exploded position.

The drawing is shaded to show contrasting appearance.

I claim:

The ornamental design for a combination lipstick holder and cigarette lighter, as shown and described.

ALBERT MONTURO.
